[57] CLAIM

The ornamental design for a safety syringe, as shown and described.

DESCRIPTION

FIG. 1 is a perspective view of a safety syringe, showing our new design, with the shield portion in the retracted position;

FIG. 2 is a side elevational view thereof;

FIG. 3 is an end elevational view thereof, taken from the left of FIG. 2;

FIG. 4 is a side elevational view thereof, with the needle sheath removed;

FIG. 5 is an end elevational view thereof, taken from the left of FIG. 4;

FIG. 6 is a side elevational view thereof, with the shield in the extended position;

FIG. 7 is a perspective view thereof, with the shield in the extended position; and

FIG. 8 is an end elevational view thereof, taken from the right of FIG. 2.
